(57) **CLAIM**

The ornamental design for a firearm suppressor assembly, as shown and described.

DESCRIPTION

FIG. 1 is a top, front, right perspective view of a firearm suppressor assembly in accordance with our new design; FIG. 2 is a top, rear, left perspective view thereof; FIG. 3 is a top view thereof; FIG. 4 is a bottom view thereof; FIG. 5 is a front view thereof; FIG. 6 is a rear view thereof; FIG. 7 is a left side view thereof; FIG. 8 is a right side view thereof; FIG. 9 is a top, front, left perspective view thereof; FIG. 10 is a bottom, rear, right perspective view thereof; FIG. 11 is a top, rear, right perspective view thereof; FIG. 12 is a vertical section of FIG. 1, along line 12-12; FIG. 13 is a horizontal section of FIG. 1, along line 13-13; FIG. 14 is a top, front, right perspective view of a first component of the firearm suppressor assembly of FIG. 1, the first component being a firearm suppressor core; FIG. 15 is a top, rear, left perspective view of the first component thereof; FIG. 16 is a top view of the first component thereof; FIG. 17 is a bottom view of the first component thereof; FIG. 18 is a front view of the first component thereof; FIG. 19 is a rear view of the first component thereof; FIG. 20 is a left side view of the first component thereof; FIG. 21 is a right side view of the first component thereof; FIG. 22 is a top, front, left perspective view of the first component thereof; FIG. 23 is a bottom, rear, right perspective view of the first component thereof; FIG. 24 is a top, rear, right perspective view of the first component thereof; FIG. 25 is a vertical section of FIG. 14, along line 25-25; FIG. 26 is a horizontal section of FIG. 14, along line 26-26;

(Continued)

FIG. 27 is a top, front, right perspective view of a second component of the firearm suppressor assembly of FIG. 1, the second component being a firearm suppressor tube;
FIG. 28 is a top, rear, left perspective view of the second component thereof;
FIG. 29 is a top view of the second component thereof;
FIG. 30 is a bottom view of the second component thereof;
FIG. 31 is a front view of the second component thereof;
FIG. 32 is a rear view of the second component thereof;
FIG. 33 is a left side view of the second component thereof;
FIG. 34 is a right side view of the second component thereof;
FIG. 35 is a vertical section of FIG. 27, along line 35-35;
FIG. 36 is a top, front, right perspective view of a third component of the firearm suppressor assembly of FIG. 1, the third component being a firearm suppressor mount body;
FIG. 37 is a top, rear, left perspective view of the third component thereof;
FIG. 38 is a top view of the third component thereof;
FIG. 39 is a bottom view of the third component thereof;
FIG. 40 is a front view of the third component thereof;
FIG. 41 is a rear view of the third component thereof;
FIG. 42 is a left side view of the third component thereof;
FIG. 43 is a right side view of the third component thereof;
FIG. 44 is a vertical section of FIG. 36, along line 44-44;
and,

FIG. 45 shows top, rear, right perspective views of the components of FIGS. 14-44, in an exploded configuration.
